FIG. 3.

FIG. 2.

Des. 187,898

PAGE 3

Fig. 4.

Fig. 1 is a front perspective view including one side and top of an incinerator for destruction of confidential papers, showing my new design;

Fig. 2 is a front elevational view of the incinerator according to Fig. 1;

Fig. 3 is a side elevational view looking at Fig. 2 from the right;

Fig. 4 is a side elevational view looking at Fig. 2 from the left;

Fig. 5 is a top plan view; and

Fig. 6 is an elevational view of the back of the incinerator.

The dominant features of the design reside in the features shown in full lines.

I claim:

The ornamental design for an incinerator for destruction of confidential papers, substantially as set forth in the drawings.
